US00D888004S

(12) **United States Design Patent** (10) Patent No.: **US D888,004 S**
(45) Date of Patent: **** Jun. 23, 2020**

(54) **RADIO CABLE SHROUD**

(71) Applicant: **ConcealFab Corporation**, Colorado Springs, CO (US)
(72) Inventors: **Carl Tompson**, Colorado Springs, CO (US); **Oliver Carson**, Colorado Springs, CO (US); **Amber Bartley**, Colorado Springs, CO (US); **Jonathan Morris**, Colorado Springs, CO (US)

(73) Assignee: **ConcealFab Corporation**, Colorado Springs, CO (US)

(**) Term: **15 Years**

(21) Appl. No.: **29/724,759**

(22) Filed: **Feb. 19, 2020**

(51) LOC (12) Cl. **14-03**

(52) U.S. Cl.

USPC **D14/140.6; D13/184**

(57) **CLAIM**

The ornamental design for a radio cable shroud, as shown and described herein.

DESCRIPTION

FIG. 1 is a perspective view of a radio cable shroud, showing the new design in use with environmental structure;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view of thereof; and,

FIG. 7 is a bottom view thereof.

The broken lines in the drawings depict environmental structure that forms no part of the claim.

1 Claim, 7 Drawing Sheets
